APPARATUS FOR MIXING FLUIDS

Jefferson B. Elliot and Fritz Klaeden,
San Antonio, Tex.

Application May 18, 1935, Serial No. 22,179

3 Claims. (Cl. 210—40)

(Granted under the act of March 3, 1883, as
amended April 30, 1928; 370 O. G. 757)

This invention described herein may be manufactured and used by or for the Government for governmental purposes, without the payment to us of any royalty thereon.

5 This invention relates to an apparatus for the introduction of foreign fluids into another fluid, more particularly it is directed to an apparatus of this character for introducing into water under pressure, flowing in a water system, a foreign 10 liquid miscible therewith for the purpose of removing scale, rust or sediment therefrom, or for purifying the water in said system, also for introducing a liquid into steam or air under pressure, and for introducing one chemical into 15 another chemical flowing in a chemical system for the purpose of obtaining a controlled mixture.

One of the objects of the invention is to provide an improved valve which is so constructed that a 20 fluid flowing through said valve will cause another fluid to be introduced into the first mentioned fluid.

Another object of the invention is to provide an apparatus for introducing a foreign fluid 25 into a liquid system including an improved valve for causing said fluid to be introduced into said system, said valve including means for controlling the amount of foreign fluid to be introduced into said system.

30 With the above and other objects in view, the invention consists in certain novel details of construction, combination and arrangement of parts, to be hereinafter more fully described and specifically pointed out in the claims.

35 In describing the invention in detail reference is had to the accompanying drawing, forming a part of this specification, and wherein like numerals of reference indicate corresponding parts throughout the several views, in which—

40 Fig. 1 is a front elevation of the apparatus with the improved valve thereof shown in section, and

Fig. 2 is a side elevation of the apparatus with parts of the valve broken away.

45 In the illustrated embodiment characterizing the invention A indicates generally the improved valve for causing a predetermined quantity of foreign fluid to be introduced into a confined stream of fluid such as water which is under 50 pressure and B indicates a container which may be provided for the foreign fluid to be introduced into the fluid stream by said valve.

The valve A comprises a body portion (1) provided with a flange (2) on each side thereof, 55 having a hollow substantially frusto-conical bell

shaped end member (3) threadably connected thereto. The frusto-conical bell shaped members (3) are provided with a boss (4) on their outer ends to which inlet and outlet pipes (5) and (6) respectively, of a fluid distributing system, are 5 adapted to be connected. Suspended within the body portion (1) is a centrally located longitudinally extending torpedo-shaped pendant member (7) which is partially circular at its middle portion and of a smaller diameter than 10 the inner circular surface (8) of the body portion (1) for a purpose which will hereinafter appear.

The torpedo-shaped pendant member (7) is formed integrally with a centrally depending 15 portion or member (10) whereby a partial annular enlarged area (9') is provided at the middle portion of the valve and is provided with a pointed end portion (11) which is substantially conical-shaped and a blunted end portion (12) 20 of a frusto-conical shape. The pointed end portion (11) is formed with reversed curves to substantially conform to the inner curvature of the bell shaped end member (3) to which the inlet pipe (5) is connected thereby providing an annular area (9) which gradually increases in its circumferential area from adjacent to the inlet side of the valve to the enlarged area (9') in which it is in alignment and the blunted end portion (13) is of a greater length than said 25 pointed end portion and is curved outwardly thereby providing an annular area (13) which gradually decreases in cross-section from the enlarged area (9') in which it is in alignment to a point (14) of greatest restriction or the least cross- 30 sectional area at its outer end adjacent to the outlet side of the valve. These areas (9), (9') and (13) provide a continuous passageway for the fluid under pressure flowing through the valve, the said passageway being annular except 35 at the middle portion of the valve, where it is only partially annular. By this construction the stream of fluid flowing through the valve is caused to be confined to a path which is cylindrical except where the supporting member (10) 40 for the pendant (7) closes a part of the cylindrical path, the said path including the graduated enlarged area (9) and the area (13) which is decreasingly graduated to the point of greatest restriction. A passage 45 is provided in the blunted end portion (12) which leads inwardly from the center at the outer end thereof in an upward direction into a bushing (16) mounted in a central bore (17).

The upper end of the bushing (16) is thread- 55

ably connected to the upper end of the bore (17) and has a flange (18) provided thereon for the application of a wrench, and the lower end thereof is closed except for an aperture (19) provided adjacent the inner end of the passage (15) and a valve opening (19') which is adjacent the inner end of a passage (20) which leads outwardly from the lower end of the bore (17) into a tapped opening (21) to which one end (22) of piping (23) is connected, the other end of said piping (23) being suitably connected to the lower end of the container B for the foreign fluid, whereby fluid in the container is adapted to enter the valve A through the passage (20) through the valve opening (19') into the lower end of the bushing (16) and thence through the aperture (19) into the passage (15), leaving at the outer end of the blunted portion (12) of the pendant member (7) where it is adapted to enter the liquid stream flowing through said valve.

The amount of foreign fluid entering the valve A is under the accurate control of a needle valve (24) which is mounted on the valve body (1), between the passages (15) and (20) and threadably connected to a packing gland (25) the lower end of the needle valve (24) cooperating with the valve opening (19) on the lower closed end of the bushing (16). The packing gland (25) is in the form of a stud and has one of its ends threadably connected in the upper end of the bushing (16) and is provided with a packing cap (26) on the other end thereof.

The container B for the foreign liquid which is preferably made of glass is suitably connected to the other end of the piping (23) and is mounted within a holder (27). A suitable check valve (28) is provided in the piping (23) to prevent back flow. In order to show the amount of flow to be controlled by the valve A the glass container B is provided with a graduated scale (29). An aperture (30) is provided in the holder (27) for viewing the liquid in the glass container B.

When the device is employed for introducing a fluid such as air into liquid under pressure, the container B may be dispensed with and the device opened to the atmosphere through the check valve (28).

In operation, after the pressure and flow of the liquid such as water flowing in the system is determined at the point where valve A is to be installed therein, the amount of foreign fluid required to be introduced into the water is then calculated for the maximum water flow through the valve. The needle valve (24) is then adjusted and set for the amount of foreign fluid to be introduced in the system. The water entering the valve A through the end member (3) to which the inlet pipe (5) is connected is caused by the pointed end portion (11) of the pendant member (7) to enter the increasingly graduated annular portion (9) of the passageway for the fluid as indicated by the arrows, and to flow into the partial annular enlarged area (9') whereby the volume of the fluid is greatly increased and thence through the decreasingly graduated area (13) to the point (14) of greatest restriction where it enters the outlet pipe (6) of the water system which leads to utilization points therefore. At the point (14) of greatest restriction, this area may be made variable for obtaining high velocities from different initial pressures of the fluid in the conduit. As long as the water flows through the valve, fast or slow, the initial pressure of the fluid flowing in the conduit acting upon the enlarged area (9') creates a very

high velocity at the point (14) of greatest restriction and a reduction in the water pressure and a vacuum is created by the greatly increased velocity of the water through the restricted area (14) (Venturi principle) which is at the point 5 where the foreign fluid enters the water stream from the outer end of the passage (15) provided in the blunted end portion (12) of the pendant member (7). Should the water flow stop, the flow of the foreign fluid therein would also stop, 10 the check valve (28) stopping any back flow as the pressure of the water builds up again, thereby eliminating the possibility of water entering the fluid container B. By this construction no pressure is required on the fluid in the container 15 to force the fluid into the valve. The action of the valve is strictly the Venturi principle wherein the pressure of the liquid in the main conduit due to its construction creates a great reduction in the initial pressure and also a vacuum at the 20 point of greatest restriction, thereby allowing the fluid in the container to flow into the valve under its own static head or even be drawn into the valve by the vacuum. This last feature however, depends upon the variable vacuum created by the 25 variable initial pressure; in other words, the greater the initial pressure the greater the vacuum will be developed.

It will thus be seen that there is provided a highly novel and useful form of valve, which is 30 well adapted for all the purposes designated, even though it has been described as comprising certain details of construction, it is nevertheless to be understood that various changes may be made without departing from the spirit or scope of the 35 invention.

Having described our invention, what we claim as new and wish to secure by Letters Patent is:

1. A valve for the introduction of a fluid into a stream of a second fluid under pressure adapted 40 to flow through said valve, comprising a substantial hollow body portion having an inlet and outlet provided thereon, a centrally located member provided in said body portion, said member having ends forming a passageway with the inner 45 surface of said body portion for said second fluid, one of the ends of said member being substantially conical-shaped and another thereof being substantially in the shape of a frustum, the said conical-shaped end of said member terminating 50 adjacent to the inlet side of said body portion and the said frustum-shaped end of said member terminating closely adjacent to the outlet side of said body portion, a central bore provided in said body portion and extending into said member, a bushing provided in said bore, passageways for said first mentioned fluid provided in said body portion and member, one of said last mentioned passageways leading from the outer surface of said body portion to said central bore 60 and another of said passageways leading from said bore to the outer end of said frustum-shaped end of said member, a valve opening provided in said bushing and a needle valve between said last mentioned passageways threadably connect- 65 ed to said bushing and adapted to control said valve opening.

2. An apparatus for the introduction into a stream of fluid under pressure flowing in a conduit, of a second fluid miscible therewith, comprising in combination a valve including an inlet and outlet side and forming a part of said conduit, a body portion provided on said valve, a pendant member provided in said body portion, a passageway for the stream of fluid flowing 75

through said valve formed by said pendant member, said passageway having a graduated enlarged area, a point of restriction and an area decreasingly graduated to said point of restriction, a central bore provided in said valve, a bushing in said bore, an aperture and valve opening in said bushing, passageways for said second fluid provided in said valve, one of said passageways leading from the point of restriction of said decreasingly graduated area to the aperture in said bushing and another of said passageways leading from said bore to the outer surface of said valve, a container for said second fluid, piping connecting said container to said last mentioned passageway, a check valve in said piping and a needle valve between said last mentioned passageways for controlling said valve opening.

3. Apparatus for mixing one fluid with another under pressure comprising in combination; a casing having a longitudinal annular passage for the pressure fluid; a chamber for the second fluid having a conduit leading into the casing; a pendant body in the casing projecting into the outlet end of said annular passage; an outlet passage for the second fluid extending through said body and discharging into the pressure fluid, said body being shaped to reduce the cross-section of the stream of the pressure fluid and produce a suction or ejector effect at the outlet of the conduit for the second fluid, and a manually operable valve to control the flow of the second fluid through said conduit.
